(21) Appl. No.: **29/146,553**

(57) **CLAIM**

(22) Filed: **Aug. 10, 2001**

The ornamental design for a portable combined motion
detector and alarm, as shown and described.

(51) LOC (7) Cl. **10-05**

DESCRIPTION

(52) U.S. Cl. **D10/106**

FIG. 1 is a front elevational view of the portable combined
motion detector and alarm of the present invention;
FIG. 2 is a rear elevational view of the portable combined
motion detector and alarm of FIG. 1;

(58) Field of Search D10/104, 106,
D10/116, 118, 121; 340/540, 541, 545,
570, 571, 572, 573

FIG. 3 is a left side elevational view of the portable
combined motion detector and alarm of FIG. 1;
FIG. 4 is a right side elevational view of the portable
combined motion detector and alarm of FIG. 1;

(56) **References Cited**

FIG. 5 is a top plan view of the portable combined motion
detector and alarm of FIG. 1; and,
FIG. 6 is a bottom plan view of the portable combined
motion detector and alarm of FIG. 1.
